[57] CLAIM

The ornamental design for a reagent cartridge for blood analysis, as shown.

DESCRIPTION

FIG. 1 is a perspective view of a reagent cartridge for blood analysis, showing my new design;

FIG. 2 is a top plan view thereof;

FIG. 3 is a front elevational view thereof;

FIG. 4 is a back elevational view thereof;

FIG. 5 is a bottom plan view thereof;

FIG. 6 is an end elevational view thereof, the opposite end being identical thereto;

FIG. 7 is a perspective view of a second embodiment of FIG. 1;

FIG. 8 is a top plan view thereof;

FIG. 9 is a front elevational view thereof;

FIG. 10 is a back elevational view thereof;

FIG. 11 is a bottom plan view thereof; and

FIG. 12 is an end elevational view thereof, the opposite end being identical thereto.
